CHAFING DISH

Harold Bloomfield, Chicago, Ill., assignor to Bloomfield
Industries, Inc., Chicago, Ill., a corporation of Illinois

Filed Aug. 19, 1960, Ser. No. 61,829

Term of patent 14 years

(Cl. D44—15)

Fig. 1 is a view in perspective of a chafing dish, showing my new design;

Fig. 2 is a top plan view thereof; and

Fig. 3 is a bottom plan view thereof.

I claim:

The ornamental design for a chafing dish, as shown.
